UNITED STATES PATENT OFFICE.

LUCIUS L. CULVER, OF ST. LOUIS, MISSOURI.

HOT-AIR FURNACE.

SPECIFICATION forming part of Letters Patent No. 369,100, dated August 30, 1887.

Application filed April 3, 1886. Serial No. 197,664. (No model.)

To all whom it may concern:

Be it known that I, LUCIUS L. CULVER, of the city of St. Louis, in the State of Missouri, have invented a certain new and useful Improvement in Hot-Air Furnaces, of which the following is a full, clear, and exact description, reference being had to the accompanying drawings, forming part of this specification, and in which—

10 Figure 1 is a front view of my improved furnace. Fig. 2 is a detail horizontal section taken on line 2 2, Fig. 1. Fig. 3 is a horizontal section taken on line 3 3, Fig. 1. Fig. 4 is a vertical transverse section taken on line 4 4, Fig. 3, looking in the direction of the arrows. Fig. 5 is a vertical longitudinal section taken on line 5 5, Fig. 1, looking in the direction of the arrows. Fig. 6 is a perspective view of the damper-plate removed. Fig. 7 is a like 15 2c view of the damper, and Fig. 8 is a perspective view of one of the diving-plates removed.

25 My invention is an improvement in those hot-air furnaces in which the entire surface of the furnace proper is utilized for the purpose of heating the air, and in which the products of combustion are so made to pass as to utilize as much as may be the heat therein; and my invention consists of features of novelty herein-after fully described, and pointed out in the 30 claims.

Referring to the drawings, A represents the brick-work or outer wall forming a chamber for the furnace; E, the furnace located within the chamber in the brick-work or outer wall, 35 and having a fire-box; B, provided with a suitable grate, C, beneath which is the ash-box D. The furnace is provided at the front end with a chute, F, through which the fuel is inserted into the fire box.

40 The front of the furnace is provided with a frame, G, having a door, H, in line with the chute F, through which the fuel is fed. Hinged to this frame is also a door, I, by which access may be had to the ash-pit through a tube, J. (See Fig. 5.) Just above the door I is a small door, K, having a slot or opening through which the shaking device of the grate may be reached. At each side of the door I is a sliding or other door, L, (see Fig. 1,) through which 45 50 access may be had to the bottom of the furnace to clean it out through tubes M, extending from the doors back across the front air-space to the furnace. (See Figs. 2 and 3.)

The side walls, E³, front wall, E⁴, rear wall, E⁵, and the top E⁶ of the furnace extend some 55 distance above the fire-box, as shown in Figs. 4 and 5, forming a chamber, E', into which the products of combustion rise from the fire-box and then pass down side flues or chambers, E², between the fire-box and ash-pit, side walls, E¹, and rear wall, E⁸, and the side walls, E³, and rear wall, E⁵, to the bottom E⁹ of the furnace, as shown by arrows, Figs. 3, 4, and 5, passing from the bottom of the side flues, E², backward and out through a short flue, N, 60 65 connecting the furnace to the lower of a series of horizontal drums or flues, N', connected, preferably, at opposite ends by short vertical tubes or flues N², the top flue, N', passing out through the brick wall, as shown in Figs. 3 70 and 4, where it may connect with a flue, chimney, or other uptake.

The products of combustion are prevented from taking the shortest course from the fire-box to the outlet-pipe N by horizontal plates 75 O, that cover the rear parts of the side flues, E², at the top of the fire-box, so that the products of combustion have to pass forward and down through the front parts of the flues E², and these parts of the flues are preferably 80 covered by horizontal plates O', with perforations O², through which the products pass. The object of the perforated plates O' is to insure an equal entrance of the products and to distribute them all along the front of the flues 85 E², preventing, to a great extent, their entering more at the ends of the plates O than farther forward. The plates O' are preferably supported by being slightly inclined, with their upper edges resting against the side 90 walls of the furnace, having projections or lips O³, (see Fig. 4,) that rest on top of the edge of the fire-box, and projections or lips O⁴, that rest against the sides of the top of the fire-box. The plates are thus firmly held in place 95 without being riveted or otherwise secured to the parts against which they bear, and they can consequently be easily and quickly inserted and removed.

To prevent the products of combustion 100 taking a short cut from the ends of the plates O to the pipe N, which would result in a loss of heat, I extend from the forward ends of the plates O down into the flues E² inclined plates O⁵, which are preferably made in one 105 piece with the plates O, as shown in Fig. 8.

By the use of these plates O^5 the products of combustion are made to pass to the bottom of the furnace at its front end as well as at its rear, and the heat is thus utilized to warm all parts of the furnace.

When it is desired to turn off the heat of the furnace, the products of combustion are allowed to pass down at the back of the fire-box to the pipe N by opening a damper, P , hinged to a plate, W , on the top of the flue E^2 at the back of the furnace and resting with its free edge on top of the back wall of the fire-box. (See Figs. 3, 4, and 5.) The damper is shown turned up in dotted lines in Fig. 5. I have shown it operated by means of a rod, Q , that extends from it outward through the brick wall of the furnace. It has a crank, R , on its outer end, by which it may be turned to operate the damper, and it has a crank, S , on its inner end, engaging a lug, T , on the damper.

The plate W meets at its ends with the inner ends of the plates O , (see Fig. 3,) so as to close with the damper the flue E^2 at the back. It has openings W' , (see Fig. 6,) which the damper closes when down, and through which the products of combustion pass when the damper is up. The damper is secured to the plate by journals W^2 thereon, fitting in lugs W^3 on the plate. The inner end of the rod Q fits in a socket, W^4 , on the plate and fits under a loop, W^5 , on the plate, and it is thus firmly held in place when turned to lift the damper. The lug or hook T is dovetailed into lugs W^6 on the damper, and held there by a screw or rivet, W^7 .

While the plates O act in connection with the plates O^5 , they cause the furnace to be thoroughly heated, and at the same time, when the heat is turned off by opening the damper P , act to prevent the furnace from being heated by preventing any heat or products of combustion from passing down the side flues, E , and they thus serve to produce two useful results. The flues N' have necks N^6 , that extend out through one wall of the brick-work and are closed by dampers or covers N^7 , and through means of which the flues can be cleaned.

Between the ends and sides of the furnace E and the outer brick wall, and entirely surrounding the furnace, is an air space or chamber, U , through which the air, entering at U' , Fig. 4, passes to exit tubes or pipes V , that carry it to the different parts of the building or other place to be heated. I prefer to close the chamber U just over the opening U' by a plate or brick-work, U^2 , so that the air will be carried well into the furnace. The air thus comes in contact with all parts of the walls of the furnace E , as indicated by the featherless arrows and the flues N , so that the greatest heating capacity of the furnace is utilized.

The walls E^2 of the ash-pit may be provided with one or more sliding dampers, Y , operated by a rod, Y' , to allow the dust to pass into the flue E^2 when the grate is shaken.

I claim as my invention—

1. The combination of the bottom plate, E^3 , the ash-box D , the fire-box B on the ash-box, having a suitable grate, the side walls, E^2 , the rear wall, E^2 , having outlet-pipe N in the lower portion, the front plate, E^4 , having feed-chute F , ash-tube J , and flue-tubes M , and a series of heating-tubes, N^2 , connected with the outlet-pipe, the side walls and rear wall forming side flues, E^2 , at the sides and rear of the ash-box and fire-box, and the front wall, rear wall, and side walls being extended upward above the fire-box and provided with a top, E^6 , forming a large combustion-chamber, E^5 , over the fire-box, substantially as described. 80

2. The combination of the bottom plate, E^3 , the ash-box D , the fire-box B , the side walls, E^2 , the rear wall, E^2 , having outlet-pipe N in the lower portion, the front plate, E^4 , having feed-chute F , ash-tube J , and flue-tubes M , 85 the plates O , covering the side flues, having downwardly-inclined plates O^5 , and the plate W , covering the rear flue, having damper P , the side walls and rear wall forming the side flues, E^2 , at the sides and rear of the ash-box and fire-box, and the front wall, rear wall, and side walls being extended upward above the fire-box and provided with a top, E^6 , forming a large combustion-chamber, E^5 , over the fire-box, substantially as described. 95

3. The combination of the side walls, E^2 , front wall, E^4 , rear wall, E^2 , bottom E^3 , top E^6 , ash-pit D , having side walls, E^2 , and rear wall, E^2 , and the fire-pot B , forming chamber E^5 at the top, and flues E^2 at the sides and rear, horizontal rear plate, W , having a damper, horizontal imperforate side plates, O , having inclined plates O^5 , the horizontal perforated side plates, O' , and a rod to the damper, substantially as shown and described. 105

4. The combination of the furnace having a fire-pot provided with side chambers, E^2 , open at the top for the passage of the products of combustion and connected with the exit-flue, the top side plates, O , the rear top plate, W , having lugs W^3 , a socket, W^4 , and a loop, W^5 , a damper, and an operating-rod, substantially as shown and described.

5. The furnace provided with side flues, E^2 , in combination with the frame W , provided with lugs W^3 , socket W^4 , loop W^5 , and the damper provided with a hook and journaled in the lugs, and the operating-rod fitting in the loop and socket and engaging beneath the hook of the damper, substantially as shown 115 and described.

6. The combination, with the plate W , of the lugs and loop formed on the plate, the damper P , hinged to the plate-lugs, having lugs W^6 , the hook T , dovetailed into the 120 damper-lugs, and an operating-rod, substantially as shown and described.

LUCIUS L. CULVER.
